(57) **CLAIM**

The ornamental design for a surge protector module, as shown and described.

DESCRIPTION

FIG. 1 is a perspective view of a surge protector module showing my new design;

FIG. 2 is a front elevational view;

FIG. 3 is a side elevational view thereof;

FIG. 4 is a rear elevational view thereof;

FIG. 5 is a view of the opposite side thereof;

FIG. 6 is a top view thereof;

FIG. 7 is a bottom view thereof; and,

FIG. 8 is an exploded front perspective view showing the removable facia.

The broken line environmental showing is for illustrative purposes only and forms no part of the claimed design.
